UNITED STATES PATENT OFFICE.

DAVID R. WAY, OF FAIRFIELD, IOWA.

ACETYLENE-GAS GENERATOR.

1,009,119.

Specification of Letters Patent. Patented Nov. 21, 1911.

Application filed March 3, 1911. Serial No. 612,003.

To all whom it may concern:

Be it known that I, DAVID R. WAY, a citizen of the United States, residing at Fairfield, in the county of Jefferson and State of Iowa, have invented certain new and useful Improvements in Acetylene-Gas Generators, of which the following is a specification, reference being had therein to the accompanying drawing.

10 This invention relates to acetylene gas generators and has for its object to provide an improved acetylene gas generator which is so constructed and arranged that it will be strongly mounted in position and will be 15 economical to construct and will be durable.

The invention further has for its object to provide an improved structure for mounting the generator in the ground.

20 The invention further has for its object to provide an improved device for gradually feeding the carbid.

The invention further has for its object to provide an improved feed device for the carbid of an acetylene gas generator which 25 will be automatic in its action and governed by the generation of the gas.

30 The invention further has for its object to provide an acetylene gas generator with an improved device for automatically registering the feed of the carbid.

With these and other objects in view, the invention consists of certain novel constructions, combinations and arrangements of parts as will be hereinafter fully described 35 and claimed.

Referring to the accompanying drawing:—Figure 1 is a view in elevation and vertical section showing an acetylene gas generator constructed and arranged in accordance with this invention and located in the ground. Fig. 2 is an enlarged detail view partly in section and broken away of a portion of the device for feeding the carbid. Fig. 3 is an enlarged detail view partly 45 broken away of a portion of the carbide feeding mechanism in one position thereof. Fig. 4 is a view similar to Fig. 3 showing another position of the feed mechanism; Fig. 5 is an enlarged detail plan view with parts 50 broken away showing a portion of the carbide feed mechanism. Fig. 6 is a view of a utensil used for removing the residuum to clean out the tank when recharging it.

Referring to the accompanying drawings, 55 the generator is inclosed in a suitable receptacle located in an excavation in the ground,

and as here shown preferably consisting of a receptacle whose walls 1 are formed of vitreous or other suitable material. The bottom of the receptacle is preferably 60 formed with a metallic plate 2 and the top of the receptacle is closed by means of a metallic flanged cover 3 resting in the shoulered annular portion 4 of the upper end of the walls 1. Suspended within the receptacle is a sheet iron bell 5 provided at its top with suitable handles 5' for handling the receptacle when placing it into and out of position and with a vent 6 in its top to permit of its removal. The lower end of 65 the bell 5 projects into the water 7 located in the main receptacle and forming a water seal between the sides of the receptacle and the bell. The bell 5 is held in a vertical position by means of angle iron brackets 8 70 on the sides of the receptacle against which the sides of the bell bear. Loosely resting on the bottom of the receptacle is a sheet metal support having tapering sides 9 resting on the bottom of the receptacle and having 75 an annular upper end 10 which extends about metallic vertical strips 11. An annular metallic band 12 is riveted to the inner side of the vertical strips 11 and is located opposite the annular portion of the metallic 80 support and the said annular portion 10 projecting up beneath the lower end of the bell 5. It will be seen that by means of this construction a strong support is provided for the vertical strips 11 and the gas will 85 be directed from the inside of the metallic support having tapering sides 9 to the inside of the bell and prevent the gas escaping from beneath the lower edge of the bell or breaking the water seal. 90

95 Mounted in the upper end of the bell is a carbide receptacle 13 of a hopper shape and provided with a flanged cover 14 which fits over an annular metallic band 15 secured to the upper ends of the vertical 100 strips 11 and to the upper rim of the hopper 13. A conical shaped shield 16, located a short distance above the mouth of the hopper 13 and mounted on the lower end of a rod 17 secured at its upper end to the cover 105 14 of the hopper 13, serves as a guide to direct the carbide toward the discharge end of the hopper, and at the same time prevents it from clogging the same. The nozzle end 18 of the hopper is secured to a disk plate 110 19 mounted on the lower end of a tube 20 which is formed at its upper end with a

shouldered enlarged portion 21 which is seated in fixed position on the top of the cover 14.

Mounted on the under side of the plate 19 and in alinement with the nozzle 18 of the hopper is a tapering spout 22 for the passage of the carbid. A number of tilting carbid chutes 23 open at each end are mounted on rods or arms 24 projecting 10 radially from a hub 25 secured to a reduced lower end portion 26 of a shaft 27 projecting up through the tube 20. As shown in Figs. 1 and 2 the position of the chutes 23 on the rods 24 is such that as the shaft 27 15 rotates the chutes 23 are carried about beneath the plate 19 and beneath the tapering spout 22. Each of the chutes 23 is hinged at one end to a rod 24 and each chute 23 has its rear portion formed with the upwardly 20 inclined extension 28 which as the chutes are carried about beneath the plate 19 ride against the under side of the latter and hold the chutes 23 in a horizontal position as shown.

25 In order that the chutes may deliver the carbid as they receive it from the hopper in passing beneath the spout 22, a suitable means is provided for releasing the chute to permit it to tilt and discharge the carbid 30 and as here shown said means preferably consists in forming the plate 19 with an upwardly curved portion 29 which when a chute passes beneath the same, permits the extension 28 of the chute to ride against, 35 the under side of the upwardly curved portion 29 which being formed with two inclines permits the chute to tilt and dump the carbid into the water as shown in Fig. 1, and as the extension 28 reaches the lower 40 end of the opposite incline the chute is moved to its normal horizontal position. In order to rotate the shaft 27 to cause this operation of the chutes, a toothed gear wheel 30 is loosely mounted on the upper 45 shouldered end of the tube 20. Secured to the upper end of the shaft 27 is a circular head 31 which is spaced from the head of the toothed wheel 30 and rests upon ball bearings consisting of balls 32 located in 50 raceways in the head 31 and in the hub of the wheel 30.

Mounted in any suitable manner in the hub 31 are a number of pawls 33 which are adapted to engage in one direction of the 55 movement of the toothed wheel 30 notches 34 in the upper side of the wheel 30 and to ride over said notches in the opposite movement of said wheel. Meshing with the wheel 30 is a rack bar 35 which is pivotally connected 60 at one end to an arm 36 secured at its upper end to a two-armed lever 37 pivotally mounted on the upper end of an upright 37'. Mounted on one end of said double armed lever 37 is a counterweight 38 and on 65 its other end is a friction wheel 39 which

bears against the under side of the top of the bell 5. By means of this construction and arrangement, as hereinbefore described, as the bell 5 rises by the increase of pressure of the generated gas, the end of the lever 37 on which the wheel 39 is mounted is permitted to rise being elevated by the counterweight 38, and the arm 36 is swung thereby so as to push forward the rack bar 35 which rotates the beveled wheel 30, the 70 notches 34 in the wheel 30 slipping past the pawls 33 and thereby imparting no motion to the shaft 27 and to the discharge chutes 23. When the gas in the bell 5 is drawn off for use to such an extent as to lower the gas 80 pressure in the bell 5, the latter descends and as it descends, the top bears on the wheel 39 and tilts the double armed lever 37 against the counterweight 38, thereby 85 swinging back the arm 36 and pulling back the rack bar 35. In this movement the rack bar 35 rotates the toothed wheel 30 in the opposite direction from that hereinafter described, and the pawls 33 engaging the notches 34, the rotation of the wheel 30, being locked to the shaft 27 by the pawls 33, causes the shaft 27 to revolve and the carbid chutes 23 to be carried around in a circle beneath the plate 19, each chute as it comes beneath the curved portion 29 of the plate 90 19 automatically dumping the carbid into the water, as shown in Fig. 1. This movement continues until the descent of the bell 5 ceases. When the shaft 27 ceases to rotate the carbid is no longer delivered to the 100 water.

Mounted on the under side of the cover 3 in any suitable manner a registry device 40, of any well-known form, is preferably 105 employed which is provided with a projection 41 acted upon by the upper end of the bell 5 so that as the bell 5 ascends and bears against the projection 41, the amount of carbid supplied to the water will be registered 110 as well as the pressure of the gas in the bell 5. The generated gas is delivered from the bell 5 through the upper curved end 42 of a pipe 43 projecting up through the bottom of the receptacle and extending out of the same and vertically outside of the receptacle 115 to form a stand pipe 44 having its upper end projecting above the ground. Said stand pipe 44 is connected with a filter 45 which in turn is connected by supply pipe 46 with a building or other place to be supplied with the gas.

In Fig. 6 is shown a utensil for removing the residuum from the receptacle when the same is to be recharged which consists of a 120 bucket 47 having a handle 48.

It will be seen that by means of this invention the generator will be thoroughly protected in the receptacle mounted in the ground and that access to the parts may readily be had through the top by removing 130

the cover. It will further be seen that the carbid may readily be fed to the water in the receptacle by the descent of the bell and that such feed of the carbid will be automatically stopped when the bell ceases to descend and that by means of this construction and arrangement of parts the operation of the generator will be automatic and the generation of gas and the supply of carbid will 10 be regular and effective in its operation.

The walls 1 which are formed of vitrified earthen tile are preferably formed in sections 49, joined together in any suitable manner, and as here shown preferably by 15 the overlapping joints 50.

Having described the invention, I claim:

1. In an apparatus of the kind described for generating acetylene gas, a receptacle, a vertical framework, a carbid hopper 20 shaped receptacle suspended from the upper end of said framework, a bell inclosing said framework and carbid receptacle, a plate mounted beneath the lower end of said carbid receptacle and having an elevated curved portion, a shaft projecting through the top of the carbid receptacle and having its lower end projecting through said plate, a number of arms on the lower end of said shaft, a tilting carbid delivering 25 chute mounted on each of said arms and having a rearwardly projecting end, said chutes being movable in a circle beneath the lower end of said carbid hopper and permitted to tilt by said elevated portion of the 30

plate, a gear mechanism on the upper end 35 of said shaft, and a counterweighted lever connected with said mechanism and bearing against the under side of the upper end of the bell.

2. In an apparatus of the kind described 40 for generating acetylene gas, a receptacle, a vertical framework, a hopper shaped carbid receptacle suspended in the upper end of said framework, a bell extending over said framework and said carbid receptacle, 45 a vertical shaft, a number of tilting carbid delivery chutes radially mounted on the lower end of said shaft and movable beneath the lower end of said carbid hopper, means for tilting said chutes one at a time, a 50 toothed gear wheel loosely mounted on the upper end of said shaft and having a number of shouldered recesses, a number of pawls on the upper end of said shaft adapted to engage said recesses in one direction 55 of movement of the toothed wheel and to slide over the same in the opposite direction thereon, a rack bar meshing with said toothed wheel, and a counterweighted lever connected with said rack bar and bearing 60 against the upper end of the bell.

In testimony whereof I hereunto affix my signature in presence of two witnesses.

DAVID R. WAY.
